UNITED STATES PATENT OFFICE.

ALBERT E. PAGE, OF BROOKLYN, NEW YORK, ASSIGNOR TO SCOTT AND WILLIAMS, INC., OF NEW YORK, N. Y., A CORPORATION OF MASSACHUSETTS.

CIRCULAR-KNITTING MACHINE.

Application filed October 31, 1925. Serial No. 65,986.

My invention relates to circular knitting machines and more particularly to yarn feeding and severing mechanism for making plated work thereon. One object of my invention is to provide simple and comprehensive means for manipulating the plating yarn fingers and cutter from the main pattern chain. Another object is to produce mechanism which is simple, accurate and easily adapted for changes of pattern.

For purposes of illustration my invention is shown and described embodied in a seamless hosiery machine of the well-known Scott & Williams type though I do not limit the application of my invention to that type.

In the drawings—

Fig. 1 is a side elevation of sufficient of a circular knitting machine to show my striping yarn control and severing mechanism making floated vertical stripes.

Fig. 2 is a similar view showing the machine making floated vertical stripes and dots;

Fig. 3 is a similar view showing the striping yarn finger raised to inoperative position and the cutter about to operate;

Fig. 4 is a rear elevation of the cutter operating means;

Fig. 5 is an enlarged detail view showing the auxiliary yarn finger feeding to the needles having long jacks;

Fig. 6 is a similar view showing the finger feeding to all the needles having jacks;

Fig. 7 is a layout of the cam ring for the needles and jacks;

Fig. 8 is a side elevation of the lower jack cam and the mechanism operating it;

Fig. 9 is a plan view of the bedplate of the machine showing the lower jack cam and some of its operating means in section on the line 9—9 of Fig. 8;

Fig. 10 is a front elevation of the tilting bracket and the trip mechanism;

Fig. 11 is a side elevation similar to Fig. 1 but showing the opposite side of the machine;

Fig. 12 is a front elevation of the pattern chain, segment gear and associated parts; while

Fig. 13 is a side elevation corresponding to Fig. 12.

In making striped work by plating it is preferable to feed the plating yarns to the needles at a point on the needle circle in advance of the throat plate, but in timed rela-

tion with the throat plate yarn, in order to produce fancy patterns such as vertical stripes and dots by means of manipulation of the needles. My invention relates to machines adapted to perform such work. It is necessary to cut off the plating yarn within a short space of time after its removal from the needles and it is another purpose of my invention to cause this cutting at the proper interval after the removal of the yarn.

In the example shown in the drawings the usual pattern chain 85 turns with the sprocket wheel 84 on the pattern chain shaft 80, and, through lugs on the right side of the pattern chain causes the main pattern drum 120 to be racked around irregularly under its control by the train of gears 122, 121, 123 (Fig. 11). The lugs on the pattern chain 85 acting through the controller 83 lower the pawl 82 on the segment gear 75 to rack the wheel 81, shaft 80 and drum 120 as desired—all as described in the patent to Robert W. Scott 1,152,850 dated September 7, 1915. The chain itself is racked every four revolutions of the needle cylinder by a pawl 87 mounted on the segment gear 75. The segment gear 75 and the main pattern drum 120 turn on a shaft 76.

There are the regular yarn fingers F pivoted on the cross pin 554 on the latch ring 550, adapted to feed yarn at the throat plate 559. The latch ring 550 is pivoted at 552, as usual, to the bracket 401 mounted on the bedplate D of the machine. For the purpose of lifting these regular yarn fingers out of action the usual thrust-bars 460 are provided, passing downwardly through an upper arm 463 on the bracket 401 and the lower comb 451 on the stud 450, to the main pattern drum 120, where they are acted on by suitable rings of drum cams 501 and 502.

In addition to the regular yarn fingers F, there is an auxiliary yarn finger F^a pivoted on the same cross pin 554 but positioned to feed a plating yarn to the circle of needles N at a point about 120 degrees ahead of the throat plate 559. For the purpose of lifting the auxiliary yarn finger F^a entirely out of action when knitting portions of the stocking where striping is not desired, a special thrust bar 570, controlled from the main pattern drum in the same manner as the usual thrust bars 460 is pivoted to the auxiliary yarn finger F^a at such a point that when a cam

501 or 502 on the main pattern drum 120 comes in contact with the thrust bar, the auxiliary yarn finger is lifted out of action.

At the point on the needle circle where the 5 auxiliary or plating yarn is fed, the needles are raised to various levels in order that striping can be obtained by varying the feeding level of the auxiliary yarn and allowing the 10 yarn to float behind the needles to which it is not fed.

While other patterns can be made with more yarn fingers, I have shown a machine using one auxiliary yarn finger, and one main yarn finger to produce vertical and horizontal 15 stripes and dots in the resulting fabric. To produce such a pattern by these means the needles can be separated into a plurality of levels at the auxiliary feeding point by means of jack 380. In the machine 20 shown in the drawings the needles on which the vertical stripes are to be knit are jackless; those where the dots are to occur have medium length jacks; and the remainder have long jacks (Figs. 5 and 6).

25 I have discovered that the feeding level of the auxiliary yarn finger can be varied for striping purposes by lugs on the left side of the pattern chain links through mechanism which will be described presently. When it 30 is desired to feed the plating yarn to all the needles having jacks, no lug is used on the left side of the pattern chain to raise the auxiliary yarn finger from its lowest position. When the plating yarn is to feed to 35 only the long jack needles a low lug is used. When the plating yarn is not to be fed to any of the needles, for a short space of time, there is a high lug on the pattern chain to lift the auxiliary finger out of action.

40 The level at which the auxiliary yarn finger feeds the yarn is determined by the position of a notched lever cam 585 pivoted on the stud 609 carrying the yarn cutter actuating lever 611. This lever cam 585 has a 45 long quick sloping surface against which an adjustment screw 586 on the auxiliary yarn finger rests when the yarn finger is in its lower feeding position (Fig. 1) and it also has a notch or shoulder on which the screw 50 rests when the yarn is in its higher feeding position (Fig. 2). When it is desired to temporarily lift the auxiliary yarn finger entirely out of action during striping, the lever cam 585 is turned up until the adjustment 55 screw 586 on the yarn finger rests on a long surface above the notch (Fig. 3). The lever cam has a depending arm engaging against a set screw 588 in the upper end of a bell crank operating lever 589 which is mounted 60 on the bedplate D of the machine by means of a bracket. This set screw 588 can be used to adjust any irregularities in the vertical position of the auxiliary yarn finger. There is a spring 587 fastened to the lever cam 65 tending to hold the depending arm against

the upper arm of the bell crank lever. It should be noted that owing to the connection between the set screw 588 and depending arm it is still possible to lift the latch ring. The exact position of this operating lever 70 589 when the auxiliary yarn finger is at its lower feeding position can be adjusted by means of a set screw 590 engaging the surface of the bedplate D of the machine.

Connected to the lower end of the bell 75 crank operating lever 589 is a vertical rod 231 secured to a horizontal arm 233 of a tilting striping bracket 232 pivoted on a stud 234 on the frame of the machine. The lower end of the vertical rod 231 is fastened to the 80 horizontal arm 233 by a screw 239 playing in a slot 240 in the rod. The movements of the bracket 232 are under the control of the pattern chain 85 through the medium of a depending arm 235 having a pin 236 overlying the left side of the pattern chain links (Fig. 10). In this way pattern chain links having low or high lugs on their left side are availed of to raise and lower the auxiliary 85 yarn finger F^a.

90 It will be observed that by means of the mechanism which has been described, both the needle cylinder and the auxiliary yarn finger are actuated in timed relation to the segment gear. The movements of the auxiliary yarn finger are so timed with relation to the revolutions of the needle cylinder that they always occur at the same wale in the knitted fabric and, if desired, these changes can be made to occur a little previously to the 95 changes of the main yarn fingers F thus bringing the changes of the auxiliary yarn finger at approximately the same wales of the knitted fabric as the changes caused by the main yarn fingers.

100 The mechanism already described can actuate the auxiliary yarn finger every four revolutions of the needle cylinder or at longer intervals if desired and the dots or horizontal stripes can be varied at will by changing the 105 links on the pattern chain. Each pattern chain link corresponds to twelve courses on the stocking or twelve revolutions of the needle cylinder, and each link is racked every four courses, three racks to the link. Therefore there are three lug positions on each link. I also provide tripping means by which the auxiliary yarn finger can be made to change its position at shorter intervals than four revolutions. This mechanism includes 110 a latch 237 pivoted on the vertical rod 231 near its lower end and adapted to engage the upper side of the horizontal arm 233 of the tilting bracket 232, and a trip rod 241 therefor. The points of pivotal connection of the 115 pattern chain, pawl 87, and the trip rod 241 to the segment gear 75 are such that for the most part the pawl and rod move in opposite directions, and the trip rod has a longer movement than does the pattern chain pawl. 120 125 130

There is a spring 238 which has the double function of holding the latch in engagement with the horizontal arm 233 and also causing the return of the auxiliary yarn finger to its lower feeding position when the latch is tripped; by pulling the vertical rod 231 downwards. When the latch is set on the upper side of the horizontal arm 233 the vertical rod and the horizontal arm are positively pivoted together with the screw 239, which links the vertical rod with the horizontal arm of the bracket, at the lower end of the slot 240 in the vertical rod. Means by which the aforementioned trip rod 241 disengages the latch from the horizontal arm 233 and allows the spring 238 to pull the vertical rod down comprise a trip wire 242 carried by the latch 237 which can be adjusted at such a height that the free end of the trip rod 241 will engage its lower end and push the latch clear of the horizontal arm. The trip rod 241 may be of flat bar material set on its narrow edge in order that the lower end of the trip wire 242 can be engaged by the trip rod when the tilting bracket has been raised by either a high or a low lug on the pattern chain. This adjustment is shown in Figs. 3 and 10. It should be observed however, that the trip wire can, if desired, be set at such a level that the trip rod will trip the latch only when the bracket has been tilted by a high lug on the pattern chain; and in that case the trip rod will miss the wire when the tilting bracket is raised by a low lug (Fig. 2). It will be seen that in this way the machine can be adjusted to produce dots and horizontal stripes each four courses wide, dots four courses wide and horizontal stripes two courses wide, or dots and horizontal stripes each two courses wide, as desired. By varying the adjustment of the trip rod other combinations can be obtained, but it is believed that the combinations above mentioned will be adequate for ordinary practical purposes.

For cutting off such yarns as are removed from the knitting, a usual clamp 606 and cutter 608 are provided inside the needle circle toward the front of the machine. It will be noted that outgoing yarns must be carried around the circle for a considerable distance from the auxiliary feeding point or the throat plate before the last needle on which the yarn was knit comes closest to the cutter 608. My invention provides for cutting the outgoing yarns when the yarn has been thus brought around through an angle which, in the case of an auxiliary yarn, is 280 degrees. One of the regular thrust bars 460^c is used to actuate the yarn cutter 608 by means of the lever 611, the cutter being controlled from the main pattern drum 120 except during striping. When it is desired to sever yarns during striping, the yarn cutter is operated from a continuously mov-

ing gear 65 revolving once for a plurality of revolutions of the needle cylinder—in the machine given in the drawings, once for every four revolutions of the needle cylinder.

This gear 65 is mounted on a shaft 55, 70 parallel to the shaft 76 on which the main pattern drum turns. On the side of the gear 65 are two cams 591 each for the purpose of actuating the cutter 608. The cams can be so positioned on the gear that the cutter 75 shears every second revolution of the needle cylinder in timed sequence to the yarn finger movements as above described. The cam movements are brought to the thrust bar 460^c by an operating lever 592 pivoted on 80 the bedplate of the machine by a bracket 593, a connecting link 596 and a bell crank lever 594 pivoted on the lower comb 451.

These cutter operating means can actuate the yarn cutter thrust bar only when the 85 tilting bracket 232 connects them together. On the tilting bracket is a vertical arm 582 with a wire link 583 passing through an eye in its upper end, the other end of the link being hooked to a dog 581 pivotally hung 90 on the yarn cutter thrust bar. Mounted on this wire link on opposite sides of the eye of the vertical arm 582 are adjustable collars 584', and between the collar on the side towards the dog and the eye of the vertical 95 arm is a spring 584 which tends to hold the toe of the dog over the bell crank operating lever. The wire link and its collars and spring can be adjusted to push the toe of the dog over the bell crank operating lever 594 100 either when the tilting bracket has been raised by a high lug on the pattern chain, or when the tilting bracket is raised by either a low or high lug.

When my invention is used on a machine 105 to which ribbed tops are transferred, means must be provided for "levelling off" the needles in order to effect this transfer. This operation includes a change in the position of the lower jack cam 366 (Figs. 7, 8 and 9) and 110 I propose to do this by lowering the point of the jack cam 366 to the position shown in dotted lines in Figure 7 by a connection with the well-known instep needle raising and lowering cam or so-called "switch cam". 115 The lower jack cam 366 is mounted inside the cam ring 271 and consists of a low stationary base 366^a and a point 366^b adapted to slide vertically in a groove on the cam ring side of the base. The butts of the jacks 380 are 120 long enough to be acted on by the point 366^b. This movable point is secured to a slide or support 209 moving in a vertical slot milled part way through the cam ring 271. On this slide 209 is a pin 210 passing through the slot in and projecting out of the cam ring 271. This pin is moved vertically by the point of operating finger 211 mounted in the base of the switch cam bracket 411. This operating finger 211 is oscillated by a winged col- 130

lar 212 secured thereto which engages against a depending arm 214 on a switch cam lever 408. The winged collar 212 is held against the depending arm 214 of the switch cam lever by a tension spring 213 in such a position that when the switch cam 415 is raised the operating finger 211 is swung upwardly raising the point of the jack cam.

The switch cam is indicated in Fig. 8 by the reference number 415. It is mounted in a bracket 411 on the bedplate D by means of spindle 410 lying in the bracket 411. There is a cam or roller slot 412 in the bracket in which lies a screw 413 having a roller thereon. The slot 412 is so shaped that when the switch cam is turned upward the screw 413 forces the spindle and cam towards the needle butts. The switch cam is operated by cams 509 and 510 on the main pattern drum 120. These cams are all in one path on the drum, that numbered 509 being low, and that numbered 510 being of full height. The switch cam is connected to its drum cams by the above-mentioned lever 408 which has a wing 409 mounted on the rear end of the spindle 410 with the wing overlying a vertical gravity rod 216. The gravity rod passes down through an opening in the bedplate D and is linked to one end of a lever 215 pivoted on a stud 124 projecting from the frame of the machine, the other end of this lever projecting into the path of the above-mentioned drum cams.

During the striping on the leg of the stocking the point 366^b of the lower jack cam 35 is raised to its full height in order that the medium and long jacks 380 may give the necessary separation of the needles N at the auxiliary feeding point. The point 366^b of the lower jack cam is held in this position 40 by the switch cam which at this time is at its full height—until the heel is reached, when the switch cam drops to its lowest position by the lever 215 riding off one of its drum cams 510, and the point of the jack cam is 45 lowered. The consequent failure of the jacks to cause separation of the needles at the auxiliary feeding point at this time is immaterial since no striping is being made during reciprocating knitting of the heel. When at 50 the end of the heel the switch cam is raised to bring the instep needles down into action again, the switch cam raises the point of the lower jack cam to operative position and the separation of the needles at the auxiliary 55 feeding point is resumed. Similarly the switch cam and the point of the lower jack cam are lowered during the toe. Coming off the toe the switch cam and the point of the lower jack cam are raised once more. The switch 60 cam drops to an intermediate point by means of the lever 215 coming onto its drum cam 509 at the time that the stocking is to be pressed off. This movement of the switch cam from its highest position to its intermediate position is sufficient to cause the point of the lower

jack cam to drop to inoperative position, thus eliminating the separation of the needles at the auxiliary feeding point and permitting levelling off of the needles for transfer purposes. The switch cam and the point of the lower jack cam are raised to their highest positions again when knitting is to be resumed. It should be noted that it was necessary to choose some intermediate position of the switch cam to bring the point of the lower jack cam to inoperative position in order that the separation of the needles at the auxiliary feeding point caused by the jacks might be stopped for levelling off purposes without at the same time causing the long butt needles to be raised by reason of the switch cam being put in its lowermost position. The mechanism which I have described permits the switch cam to move to its lowermost position, when desired, without requiring the point of the lower jack cam to drop any further than is permitted when the switch cam is in its intermediate position. (The operation of the point of the lower jack cam is not in any way varied by the operations which are now to be described).

Assuming that the machine is to make a pattern consisting of a four course horizontal stripe, four courses during which only vertical stripes are to be made, four courses containing vertical stripes and dots, and four courses containing only vertical stripes, the operation of the mechanism is as follows.

The first horizontal stripe is started by a rack of the pattern chain 85 which racks the main pattern drum 120 causing the special auxiliary yarn finger thrust bar 570 and the main plating yarn finger thrust bar 460 to ride off their cams 502 and drop their fingers into action. At the same time the main yarn fingers F which were feeding yarn are withdrawn from action by cams on the main pattern drum. The same racking of the pattern chain which causes this change of the auxiliary and main yarn fingers also brings a high lug on the left side of the pattern chain under the pin 236 of the tilting bracket 232. This tilts the bracket to its highest point (see Fig. 3) at the same time that the main pattern drum is racked, thus keeping the auxiliary yarn finger in inoperative position, and leaving the yarn from the main yarn finger to be knit in alone, and forming the horizontal stripe. The tilting of the bracket to its highest point as described also causes the dog 581 on the thrust bar 460^c to project over the bell crank lever 596. The cams 591 on the gear 65 are so positioned with relation to the movements of the pattern chain that at the proper time within the first revolution after the tilting of the bracket 232, one of the cams will cause the bell crank lever 594 and the thrust rod 460^c to be actuated, opening and closing the yarn cutter 608 in timed sequence as already described. The

yarn cutter will then shear any yarn coming out of action at this racking of the pattern chain as the last needle to which that yarn was fed comes near the cutter.

- 5 At the end of four courses the pawl 87 will again rack the pattern chain 85 and the pin 236 on the depending arm of the bracket will drop off the high lug onto a portion of a link which has no lug on it (see Fig. 1).
 10 The dog 581 thereupon withdraws from engagement with the bell crank lever 594, disengaging the yarn cutter from its operating means. Simultaneously the tilting bracket allows the auxiliary yarn finger to drop to its lower feeding position (Fig. 6) where its adjusting screw 586 rests on the long low slope of the notched lever cam 585. In this position the auxiliary yarn finger feeds yarn to all the needles having jacks but not to the 20 jackless needles. As these jackless needles come to the clearing cam 360 (Fig. 7) they are raised slightly in the usual manner and this auxiliary yarn is floated behind the jackless needles, thus forming vertical stripes.
 25 At the end of four courses the pawl 87 again racks the pattern chain and the bracket 232 is tilted to the position shown in Fig. 2 by a low lug on the left side of the pattern chain. In this position the auxiliary yarn finger is 30 raised to its upper feeding position and the auxiliary yarn is fed only to the needles having long jacks (Fig. 5). This causes the yarn to be floated in back of not only the needles on which the vertical stripes are being 35 made but also the needles on which dots are desired. The adjustment of the wire link 583 when making the fabric now being described is such that the tilting of the bracket 232 by a low lug on the left side of the pattern 40 chain does not cause the dog 581 to engage the bell crank lever 594.

After making four courses with the striping mechanism in this position the racking of the pattern chain causes the pin 236 to drop off its low lug onto a portion of a link having no lug and four courses are knitted with vertical stripes only, as previously described. The pattern can be repeated as desired.

- 50 When the leg of the stocking has been finished the cams 501 will be racked under the foot of the yarn cutter thrust bar 460° and the auxiliary yarn finger thrust bar 570 lifting them out of action; and any desired 55 change in the yarns fed by the main yarn fingers F will be accomplished in a similar manner. At the end of the heel the yarn cutter and the auxiliary yarn finger thrust bar ride off the cam 501 and striping will 60 continue through the foot under the influence of lugs on the left side of the pattern chain. At the end of the foot thrust bars 460° and 570 will again be raised, this time by the cam 502 and these cams will keep the auxiliary yarn finger out of action until

striping is to be commenced on the next stocking. The yarn cutter 608 can of course be operated at any desired time by the cams on the main pattern drum underlying the foot of its thrust bar 460°.

When it is desired to vary the pattern whose manufacture has just been described by making the horizontal stripe only two instead of four courses wide, the tripping means are adjusted and brought into play in the manner which will now be described.

The trip wire 242 is mounted in the latch 237, and for the particular pattern just mentioned the lower hooked end of the trip wire should be adjusted at the level shown in Figs. 80

1 and 2. With this adjustment the trip wire will not be affected by the trip rod when the tilting bracket is on no lug or a low lug, the lower hooked end of the wire lying below the rod.

When the auxiliary yarn finger is 85 raised to inoperative position and a horizontal stripe is being made (Fig. 3) the hook end of the wire is vertically opposite the trip rod 241.

The trip rod is of such a length and is attached to the segment gear 75 in such manner that at the end of the second course after the rack of the pattern chain which brought the tilting bracket and trip mechanism to the position of Fig. 3, the trip

rod will hit the lower end of the trip wire and free the latch 237 on the upper side of the horizontal arm 233.

The spring 238 thereupon pulls the vertical rod 231 downwardly, tilting the bell crank operating lever 589 away from the lever cam 585 and returning the auxiliary yarn finger to its lower feeding position where it resumes feeding to all needles having jacks.

In this way the knitting of courses having only vertical stripes is resumed after two courses.

At the end of two more courses the pattern chain will be racked again, and the tilting bracket will drop off the high lug onto a portion of the link where there is no lug, thus setting the latch on the horizontal arm 233.

The knitting of the pattern will then continue as in the previous pattern.

If it is desired to further vary the pattern whose production was described above by not only making the horizontal stripe two courses wide but also by reducing the number of courses in which the dots appear the trip wire 242 should be set at such a height that the trip rod 241 will engage same when the

tilting bracket is raised by either a high or a low lug on the pattern chain. The two course horizontal stripe will then be made in the manner described in the previous paragraph.

After the two courses made before the pin 120 236 is racked off the high lug are completed four similar courses containing only vertical stripes are made while the pin is on a portion of the pattern chain having no lug.

Then the tilting bracket is raised to its in- 125 130

termediate position by a low lug and two courses are made in which the auxiliary yarn is brought behind both the jackless and the medium jack needles. The trip wire being 5 opposite the lower part of the end of the trip rod 241 that trip rod will trip the latch at the end of these two courses and the auxiliary yarn finger will resume feeding to all the needles having jacks. At the end of two 10 more courses the tilting bracket will be lowered off the high lug onto a portion of a link which has no lug and the screw 239 returns to the bottom of the slot 240 in the vertical rod 231. The auxiliary yarn finger continues 15 to feed yarn to all the needles having jacks. At the end of these courses in which fabric is thus made containing only vertical stripes, the pattern can be repeated as many times as desired by insertion of the proper links 20 on the pattern chain.

It should be noted that there is no difficulty about timing the striping patterns with relation to the other operations of the machine since the pattern indications are placed directly 25 on the continuously racked pattern chain carrying all the other pattern indications. It should be further noted that this pattern chain is racked steadily and in time with the article being knit, in distinction to 30 the pattern means ordinarily used for controlling striping mechanisms.

What I claim is:

1. A circular knitting machine having a pattern chain, and a pattern drum racked under the control of the pattern chain, in combination with a yarn finger adapted to be actuated from said pattern drum and mechanism adapted to transmit directly to the yarn finger the movements given it by the lugs of 40 the pattern chain.

2. A circular knitting machine having a segment gear, a pattern chain racked by said segment gear, and a pattern drum racked under the control of the pattern chain, in combination 45 with a yarn finger adapted to be actuated from said pattern drum and mechanism adapted to transmit directly to the yarn finger the movements given it by the lugs of the pattern chain.

3. A circular knitting machine having a pattern chain, a yarn finger, and mechanism operated directly by the pattern chain adapted to raise said yarn finger, in combination with tripping means for said raising means 50 operated from a moving part of the machine to cause said yarn finger to be lowered without lowering the raising means.

4. A circular knitting machine having a segment gear, a pattern chain racked by said segment gear, a yarn finger, and mechanism operated directly by the pattern chain adapted to raise said yarn finger, in combination with tripping means for said raising means 55 actuated by the segment gear adapted to

cause said yarn finger to be lowered without lowering the raising means.

5. A circular knitting machine having a yarn finger, a yarn cutter and a pattern chain, in combination with means to operate said cutter, mechanism operated directly by said pattern chain to connect said cutter to its operating means and to raise said yarn finger, and tripping means for said connecting and raising means operated from a moving part of 70 the machine to cause said yarn finger to be lowered without lowering the raising means.

6. A circular knitting machine having a yarn finger, a yarn cutter and a pattern chain, in combination with means to operate said cutter, mechanism operated directly by said pattern chain to connect said cutter to its operating means and to raise said yarn finger, and tripping means for said connecting and raising means operated from a moving part 80 of the machine to cause said yarn finger to return to its lowest position without lowering the raising means.

7. A circular knitting machine having a segment gear, a yarn finger, a yarn cutter and a pattern chain in combination with means to operate said cutter, mechanism operated by said pattern chain to connect said cutter to its operating means and to raise said yarn finger from its lowest position, and tripping 90 means operated from said segment gear adapted to cause said yarn finger to return to its lowest position.

8. A circular knitting machine having a segment gear, a yarn finger, a yarn cutter and a pattern chain adapted to be racked from said segment gear, in combination with means to operate said cutter, mechanism operated by said pattern chain to connect said cutter to its operating means and to raise said 100 yarn finger from its lowest position, and tripping means operated from said segment gear, adapted to cause said yarn finger to return to its lowest position.

9. A circular knitting machine having a segment gear, a yarn finger, a yarn cutter and a pattern chain adapted to be racked from said segment gear in combination with means adapted to operate said cutter in timed sequence to the yarn finger movements and mechanism operated by the pattern chain to connect said cutter to its operating means and to actuate said yarn finger, and tripping means operated from said segment gear adopted to cause said yarn finger to return to 110 its operative position.

10. A circular knitting machine having a segment gear, a yarn finger, a yarn cutter and a pattern chain adapted to be racked from said segment gear in combination with means including an element revolving once for a plurality of revolutions of the needle cylinder adapted to operate said yarn cutter, and mechanism operated by the pattern chain adapted to connect said cutter to its operat- 125 130

ing means and to raise said yarn finger from its lowest position.

11. A circular knitting machine having a segment gear, a yarn finger, a yarn cutter and a pattern chain adapted to be racked from said segment gear in combination with means including an element revolving once for a plurality of revolutions of the needle cylinder, adapted to operate said cutter, mechanism operated by said pattern chain adapted to raise said yarn finger to inoperative position and connect said cutter to its operating means and tripping means operated from said segment gear adapted to cause said yarn finger to return to operative position.

12. A circular knitting machine having a segment gear, a yarn cutter and a pattern chain with lugs of two heights thereon adapted to be racked from said segment gear, in combination with means adapted to operate said yarn cutter in timed sequence to the yarn finger movements, mechanism operated by said pattern chain adapted to raise said yarn finger to a higher feeding position or inoperative position according to the height of the lug on the pattern chain, and tripping means operated from said segment gear adapted to cause said yarn finger to return to its lowest position when raised to inoperative position; substantially as described.

13. A circular knitting machine having main yarn fingers adapted to feed yarns at one point on the needle cylinder, an auxiliary yarn finger adapted to feed yarn at another point on the needle cylinder, a yarn cutter and a pattern chain, in combination with means to operate said yarn cutter, mechanism operated by said pattern chain to raise said auxiliary yarn finger and to connect said cutter to its operating means, and tripping means operated from a moving part of the machine to cause said yarn finger to be lowered.

14. A circular knitting machine having a pattern chain and a pattern drum racked under the control of lugs on the pattern chain, a yarn finger adapted to be actuated from said pattern drum, and mechanism operated directly by the pattern chain adapted to actuate said yarn finger without reference to the pattern drum, in combination with an instep raising and lowering cam operated from said pattern drum, needle jacks and a lower jack cam adapted to be lowered by the instep cam for levelling-off the needles, substantially as described.

In testimony whereof I have signed my name to this specification.

ALBERT E. PAGE.
